Primary Examiner — Philip S Hyder(74) *Attorney, Agent, or Firm* — Dority & Manning, P.A.(57) **CLAIM**

The ornamental design for a hand tool collet as shown and described.

DESCRIPTION

FIG. 1 is a perspective view of a hand tool collet;
 FIG. 2 is a front view of the hand tool collet of FIG. 1;
 FIG. 3 is a rear view of the hand tool collet of FIG. 1;
 FIG. 4 is a right side view of the hand tool collet of FIG. 1;
 FIG. 5 is a left side view of the hand tool collet of FIG. 1;
 FIG. 6 is a top view of the hand tool collet of FIG. 1; and,
 FIG. 7 is a bottom view of the hand tool collet of FIG. 1.
 The broken lines illustrate portions of the design that form no part of the claim.

1 Claim, 3 Drawing Sheets(56)
